Patented Dec. 21, 1915.

UNITED STATES PATENT OFFICE.

CHARLES E. DODD, OF WILLIAMSPORT, PENNSYLVANIA

CAN-OPENER.

1,164,793.

Specification of Letters Patent. Patented Dec. 21, 1915.

Application filed May 13, 1915. Serial No. 27,891.

To all whom it may concern:

Be it known that I, CHARLES E. DODD, a citizen of the United States, residing at Williamsport, in the county of Lycoming and State of Pennsylvania, have invented 5 certain new and useful Improvements in Can-Openers, of which the following is a specification.

My invention relates to an improvement 10 in can-openers, and the object is to provide a simple device of the character specified, in which the blade which cuts the tin has a full sweep practically throughout its length, and the opener is fulcrumed through a 15 sharp edge on the upper edge of the can to prevent slipping.

The invention consists in a blade having a sharpened outer edge with a general curve, a shield held adjacent to the blade with a 20 sharpened lower edge adapted to rest on the edge of the can, and certain details whereby the shield is held upon the blade and between the blade and handle.

In the accompanying drawings:—Figure 25 1 is a view in perspective; Fig. 2 is a view in side elevation partly in section and showing the first position of the can-opener; Fig. 3 is a similar view showing another position of the opener after a cut is partly 30 completed; Fig. 4 is a view of the shield; Fig. 5 shows the blade and tang with the shield on the tang before entering the notch; Fig. 6 shows it in the notch preparatory to being swung over the shoulder; Fig. 7 shows 35 the can opener in position cutting off the top of the can; and Fig. 8 is a slightly modified construction.

The numeral 1 represents the blade, which has a general curve at its cutting edge 2, 40 tapering down to a point 3, which is sharp and facilitates making the first puncture in the can.

The numeral 4 indicates a heel, which limits the insertion of the blade in the can, 45 as shown in Fig. 2, when the initial puncture is made, thus preventing the blade from being inserted unnecessarily far.

The tang 5 is adapted to be inserted into the handle 6 in the usual way, and the lower 50 edge of this tang is provided with a notch 7, and the upper edge with a shoulder 8.

The shield 9 has a slot 10 of a length corresponding to the thickness between the inner end of the notch 7 and the outer end 55 of the shoulder 8, as shown in Fig. 2, so that the slot fits this portion snugly.

The lower edge of the shield is bent forwardly, as at 11, and is sharp at its extreme edge, as at 12, by which it engages the edges of the can and is prevented from slipping, as the can opener is fulcrumed in pressing the hand downwardly and in the upward cutting action of the blade 1.

By reason of the notch 7 and shoulder 8, and the fitting of the slot 10 in shield 9 in 65 and around these parts, the pressure of the shield is in the notch 7 and on the projection 13 above the shoulder 8, thus taking it from the end of the handle, so that all the handle does is to increase the length of 70 the tang 5, and afford a grip for the operator, and a sufficient leverage to make it convenient to operate the tool.

The shield might be slightly modified, as shown in Fig. 5, in which instance it is 75 folded over or doubled, thus presenting a second edge 14 which follows the edge 12 to form another fulcrum toward the end of the cut, thus taking some of the pressure from the sharp edge 12.

In Figs. 5 and 6, the shield 9 is shown in two different positions of assembly. In Fig. 5, it is nearly on the tang before it reaches the notch 7, whereas in Fig. 6 it has been placed in the notch 7, but not yet swung 80 over the shoulder 8 or against the shoulder 13. As explained, so far as the pressure on the handle 6, that is merely to afford a grip and the required leverage, but the pressure upon the sharpened edge of the shield only 85 causes the upper end to press the more firmly against the shoulder 13, and the lower end against the rear of the notch 7, so that all strain is between the shield and the notch and shoulder.

With this can opener, it is possible to make a clean cut close to the very edge of the can, thus avoiding the usual jagged edge, and this is partly due to the shape of the cutting edge 2, although the handle of the blade has much to do with it, and the special construction of shield with its bearing at 12 upon the edge of the can, and the fitting of the slot 10 of the shield above in the notch and around shoulder 8 and pressing against shoulder 13, is of almost equal 95 importance.

I claim:—

1. A can opener comprising a blade, an integral tang, and a separable shield, the 110 blade and tang at their juncture having a notch at one edge and a shoulder at the op-

posite point, and the shield having a slot of a length equal to the distance between the inner end of the notch and the outer edge of the shoulder, whereby the slot fits these portions, the shield bent forwardly at the lower edge and sharpened to form a bearing on the edge of the can as the opener is operated.

2. A can opener comprising a blade and tang made in one piece, the blade having a general curve at one edge which is sharpened and a shoulder adjacent thereto pro-

vided with a heel at the opposite edge and having a notch back of the heel, said heel adapted to limit the extent to which the blade is inserted, and a detachable shield having a slot whereby to receive the tang and have one edge enter the notch and the other rest upon the shoulder, and a handle which holds the shield between itself and the shoulder and heel of the blade.

In testimony whereof I affix my signature.

CHARLES E. DODD.
